UNITED STATES PATENT OFFICE.

JOHN FUITE, OF GRAND JUNCTION, COLORADO.

EARTH AUGER.

Application filed March 28, 1923. Serial No. 627,620.

To all whom it may concern:

Be it known that I, JOHN FUITE, a citizen of the United States, residing at Grand Junction, Mesa County, Colorado, have invented a new and useful Earth Auger, of which the following is a specification.

This invention relates to earth augers for drilling holes in the earth.

Other objects will appear from the following description, reference being made to the drawing in which—

Fig. 1 is a side elevation of one embodiment of the invention.

Fig. 2 is a detailed view showing the construction by which water may be delivered to the bit when the device is in use.

The invention as shown comprises sections of pipe connected together to form a crank 1 with a water inlet pipe 2 at one end and a pipe 3 at the opposite end in axial alignment with the pipe 2. The pipe 3 constitutes the pipe that is to be placed in the ground so that after the hole is bored the auger is disconnected from said pipe 3, leaving the latter in the ground for connection with the water supply system.

The bit comprises a section of pipe 4 attached to the pipe 3 by a union 5 through which water is admitted into the pipe 4, and said pipe 4 is pressed to form a bit comprising two cutting blades or points 6 separated by a space 7. Water is discharged from the pipe 4 to the bit through an opening 8 (Fig. 2) thus softening the earth at that point and facilitating the boring. By means of this flow of water pebbles and small boulders may be forced aside with slight delay, the stream of water pouring against them and softening the earth in which they are imbedded while the bit is forcing them to new positions in the softened earth.

The end of the pipe 2 has swivel connection 9 with a pipe section 10 to which a water hose 11 is connected. The pipe section 10 is equipped with a valve 12 whereby the flow of water may be regulated.

It will be understood that various lengths of pipe sections 3 may be employed so as to permit use of the auger to bore for short or relatively great distances, as desired. The operator knowing the direction and the distance to be bored is thereby informed when the boring has been carried to the desired point for connection with the water main or other part. When the hole

has been bored the distance desired the water is turned off by the valve 12 and the auger removed leaving the pipe 3 in the ground for connection with the water main 60 and the piping of the house or building.

From the foregoing it will be seen that my invention is a highly useful one in the placing of pipes in the ground for connection with water mains or other purposes, 65 and that it avoids the labor, expense and defacement involved in the digging of ditches or trenches. It will be understood, of course, that when one section of the pipe 3 reaches its length in the ground, the 70 crank may be disconnected from it and another pipe section connected thereto, to which the crank will be attached to force the connected pipe sections 3 into the 75 ground. In this way connected pipe sections of relatively great length may be placed in the ground.

I am aware that the construction and arrangement of the parts may be varied without departure from the nature and principle of the invention, and I do not restrict myself unessentially, but what I claim and desire to secure by Letters Patent is:

1. An earth auger comprising a section of pipe having its walls at one end flat 80 against each other and split longitudinally from the outer end thereof and forming two blades of double thickness of the wall of the pipe and of greater width than the diameter of the pipe.

2. An earth auger comprising a section of pipe having its walls at one end flat 85 against each other forming a portion of double thickness of the wall of the pipe and of relatively much greater width than the 90 diameter of the pipe, and having a slot extending from the outer end thereof and opening into the pipe beyond said flat portion.

3. An earth auger comprising a section of pipe having its walls at one end flat against 100 each other forming a portion of double thickness of the wall of the pipe and of relatively much greater width than the diameter of the pipe and having a slot extending from the outer end thereof and opening into the pipe, the extremities of said flat portion extending at opposite angles from 105 said flat portion, means for rotating said section of pipe, and means for admitting 110 water into said section of pipe.

JOHN FUITE.
